ATTYS.

UNITED STATES PATENT OFFICE.

GEORGE C. BEIRWIRTH, OF CANTON, OHIO.

ROLLING-MILL GUIDE.

1,329,743.

Specification of Letters Patent.

Patented Feb. 3, 1920.

Application filed July 25, 1919. Serial No. 313,875.

To all whom it may concern:

Be it known that I, GEORGE C. BEIRWIRTH, a citizen of the United States, residing at Canton, in the county of Stark and State of Ohio, have invented a new and useful Rolling-Mill Guide, of which the following is a specification.

This invention relates to improvements in rolling mill guides and more particularly to 10 the construction of the guide rest bars and guide plates.

The objects of the invention are to improve the construction of guides for rolling mills, to prevent the sheets or plates as they 15 pass from the mill from accidentally displacing the guide plates, thus preventing serious accident to the mill workers; and to generally simplify and improve rolling mill guides.

With these objects in view the invention 20 consists in the novel construction and arrangement of parts hereinafter described, illustrated in the accompanying drawings and particularly pointed out in the appended 25 claims, it being understood that various changes in the form, proportions, size and minor details of construction may be made within the scope of the appended claims, without departing from the spirit or sacrificing any of the advantages of the invention.

The invention thus set forth in general terms is illustrated in the accompanying drawings forming part hereof, in which—

Figure 1 is a vertical sectional view 35 through a rolling mill provided with my guide.

Fig. 2 is a detail perspective view of one of the guide plates.

Fig. 3 is a detail perspective view of one 40 of the catchers.

Fig. 4 is a detail perspective view of one of the brackets which carries the guides.

Fig. 5 is a detail perspective view of a 45 modified form of guide bar.

A practical embodiment of the invention is disclosed in the accompanying drawings, forming a part of this specification in which similar numerals of reference indicate corresponding parts throughout the several views.

The rolls 1, housings 2 and base members 3 are of any well known construction, the housing being slidably mounted upon the 50 base members in the usual manner.

The forwardly curved bracket 4 is pro-

vided with a base plate 5 and with a downwardly disposed rib 6 which is located in the slot 7 of the adjacent base member, the upper end of said bracket being provided with 60 a rest bar 8 within the upper face of which is provided a groove 9 which is curved downwardly and rearwardly in cross section as shown in 10. A bolt 10' is passed through the base plate 5 of the bracket and connects 65 the bracket to the adjacent base member.

The guide plate 11 is preferably bifurcated at its rear end as shown at 12 and provided with the downwardly and rearwardly curved edge 13 designed to fit within the 70 groove 9. The rear side of the rest bar 8 is provided with the sockets 14 adapted to accommodate the down-turned ends 15 of the horns 16.

A modified form of the device is shown in 75 Fig. 5 in which the rest bar 17 takes the place of the rest bar 8, said rest bar being provided at its extremities with the reduced lugs 18 arranged to be received in suitable sockets in the housing of the mill. This rest 80 bar is provided with a groove 19, similar to the groove 9 in the rest bar 8 and with sockets 20 similar to the sockets 14 in the rest bar 8.

With the usual form of guide plates accidents are frequently caused by a sheet or plate emerging from the rolls forcing the guide plate out of contact with the rest bar often causing serious injury to the workmen. Such accidents are usually caused by one 90 plate or sheet which having passed from the rolls, tips the free end of the guide plate upwardly as it passes over the rear end of the guide plate. As a second sheet or plate emerges from the rolls, if the guide plate is 95 tipped up, instead of passing over the guide plate, the sheet or plate will be likely to strike the edge of the guide plate forcing it out of engagement with the rest bar and endangering the lives of any workmen in the 100 vicinity of the mill. With the present construction it is impossible for a sheet or plate passing from the rolls to tip the end of the guide plate up in the manner above described and thus danger of forcing the guide 105 plate out of the mill is obviated, the curved end 13 of the guide plate fitting snugly within the curved groove 9 and preventing accidental displacement of the guide plate.

Although the drawings and above specification disclose the best mode in which I have contemplated embodying my invention

I desire to be not limited to the details of such disclosure, for, in the further practical application of my invention, many changes in form and construction may be made, as circumstances require or experience suggests, without departing from the spirit of the invention, within the scope of the appended claims.

I claim:—

- 10 1. A guide for rolling mills including a rest bar provided with a downwardly and rearwardly curved slot and a guide plate provided with a downwardly and rearwardly curved edge located within said slot.
- 15 2. In a rolling mill, a base plate, a forwardly curved bracket mounted upon said base plate, a rest bar located at the upper end of said bracket and provided with a downwardly and rearwardly curved slot and a guide plate provided with a down-
- 20

wardly and rearwardly curved edge located in said slot.

25 3. A guide for rolling mills, including a rest bar provided with a downwardly and rearwardly curved slot, a guide plate having a downwardly and rearwardly curved edge fitting in said slot and a pair of horns connected to the rear side of said rest bar.

4. In a rolling mill, a slotted base member, a forwardly curved bracket provided with a rib located within the slotted base member, a rest bar located at the upper end of said bracket, said rest bar provided with a downwardly and rearwardly curved slot and a guide plate provided with a downwardly and rearwardly curved edge located in said slot.

30 In testimony that I claim the above, I have hereunto subscribed my name.

GEORGE C. BEIRWIRTH.
